United States Patent Office.

LUDWIG JARCHOW, OF NEW YORK, N. Y.

Letters Patent No. 97,643, dated December 7, 1869.

IMPROVEMENT IN FASTENINGS FOR CORSETS.

The Schedule referred to in these Letters Patent and making part of the same.

To all whom it may concern:

Be it known that I, LUDWIG JARCHOW, of the city, county, and State of New York, have invented a new and improved Corset-Fastening; and I do hereby declare the following to be a full, clear, and exact description thereof, which will enable those skilled in the art to make and use the same, reference being had to the accompanying drawing, forming part of this specification, in which drawing—

Figure 1 represents a plan of this invention, showing the fastening attached to the corset-springs.

Figure 2 is a detached plan of the fastening, on a larger scale than the previous figure.

Figure 3 is a side elevation of the same.

Figure 4 is a transverse section of the same, the lines $x\ x$ and $y\ y$, in fig. 2, indicating the planes of section.

Similar letters indicate corresponding parts.

This invention relates to a corset-fastening, which is composed of a flanged triangular button, and a corresponding triangular socket, said button and socket being formed in such a manner, that they lock the two springs of a corset firmly together, against a strain, transversely to the length of said springs, while the button is free to move in the socket a short distance in the direction of the length of said springs, whereby the spreading of the leaves composing such spring is obviated, and the covering of said springs is saved from injury, which it sustains if the leaves are liable to spread.

In the drawing—

The letter A represents the socket, and the letter B, the triangular flanged button, composing my corset-fastening.

The socket A is secured to a base-plate, a , which is perforated with holes to receive rivets, for the purpose of attaching it to one of the springs C, and said socket is open at its inner, and closed at its outer end, as shown in fig. 4, and it is so formed that it freely admits the button B.

This button is attached to a base-plate, b , which is

riveted to one of the springs C, as shown in fig. 1, and said button is provided, on its outer end, with a flange, c , which abuts against the inner edge of the socket, when the two parts of the fastening are united and exposed to a strain in the direction transversely to the length of the springs C.

The button B, however, is made somewhat smaller than the socket A, so that it has a certain play in the direction of the length of the springs C.

The object of this arrangement is as follows:

The springs C are generally made of two leaves, fastened together by the rivets, which also serve to attach the base-plates a and b , of the fastenings, and by additional rivets passing through their ends.

If the springs are attached to a corset, they have to follow the motion of the body of the person wearing said corset, and in being bent, now in this direction and then in the other, the leaves composing the springs are liable to spread, and to cut the covering of cloth, or other material, by which they are surrounded.

This difficulty is obviated by allowing the buttons B a small amount of play in their sockets, in the direction of the length of the springs, while they have a firm hold against a strain transversely to the springs.

My fastening is easily made, and readily fastened and unfastened.

What I claim as new, and desire to secure by Letters Patent, is—

As a corset-fastening, the plates $a\ b$, having on their inner ends the angular hollow projection A, and the solid projection B, adapted to engage with each other, to fasten, or be detached to unfasten the corset, the said parts being constructed and operating substantially as shown and described.

This specification signed by me, this 6th day of September, 1869.

LUDWIG JARCHOW.
